UNITED STATES PATENT OFFICE

2,436,389

REFRIGERATING PLATE AND INTERNAL
REINFORCEMENT THEREFOR

Herman W. Kleist, Chicago, Ill., assignor to Dole
Refrigerating Company, Chicago, Ill., a corpora-
tion of Illinois

Application September 4, 1945, Serial No. 614,420

3 Claims. (Cl. 62—126)

1

My invention relates to an improvement in refrigeration and relates particularly to the structure of cold plates.

One purpose is to provide an improved cold plate for refrigerators and the like.

Another purpose is to provide an improved plate in which a variable volume of liquid is employed within the plate, either to provide a hold-over factor, or better heat transfer, or both.

Another purpose is to provide a vacuum plate structure which is adapted to resist heavy pressures, and a coil structure which is adapted to serve as a reinforcement to the vacuum plate structure.

Other purposes will appear from time to time in the course of the specification and claims.

I illustrate the invention more or less diagrammatically in the accompanying drawings, wherein:

Figure 1 is a side elevation with parts in skeleton outline and parts broken away;

Figure 2 is a section on an enlarged scale on the line 2—2 of Figure 1;

Figure 3 is a detail section on a still larger scale;

Figure 4 is a section on the line 4—4 of Figure 3; and

Figure 5 is a detail section on the line 5—5 of Figure 2.

Figure 6 is a vertical section on an enlarged scale of an embodiment in which but a small amount of eutectic fluid is used.

Like parts are indicated by like symbols throughout the specification and drawings.

Referring to the drawings A indicates generally a cold plate including a coil in circuit with a mechanical refrigeration mechanism. The mechanical refrigeration mechanism is diagrammatically shown at B. It includes a base 1, any suitable compressor 2, driven by a motor 3 through the belt 4. I diagrammatically indicates any suitable condenser coil and 6 is any suitable receiver. 7 is a high pressure duct extending from the receiver to any suitable expansion valve diagrammatically indicated as at 8. 9 is a refrigerant delivery duct extending from the expansion valve 8 and adapted to deliver liquid refrigerant, for evaporation, to the below described evaporator structure. 10 is a low pressure return duct adapted to return the evaporated refrigerant to the compressor. Referring more specifically to the cold plate which is included in the above mentioned cycle I employ a coil which includes a plurality of rectangular and preferable rectilinear pipe lengths 15. These

2

pipe lengths may conveniently be assembled in groups of like length. Two such groups are shown in Figure 1 forming an upper coil C and a lower coil D. The employment of rectilinear pipes provides a coil having flat faces defined by parallel planes. This arrangement is ideal for use in cold plates.

Referring, for example, to Figure 2, I employ a plate having parallel walls 16 and 17 which are sealed together at their edges, for example, by the employment of flanges 18 on one such wall welded or otherwise secured as at 19 to the opposite wall. The coil formed of the rectangular tube lengths 15 therefore abuts against the inner faces of the walls 16 and 17 with a maximum area of close contact. In forming coils of rectangular cross section, it is not advantageous to bend the coil. I may find it advantageous to employ preformed couplings or connectors which may be bent or otherwise formed from tubing which is not rectangular in cross section. Referring for example to Figures 3 and 4, I illustrate connectors 20 which may be bent or otherwise formed from tubing having a generally circular cross section, each such connector may terminate at each end in a single common plane as at 21, 22. Such a connector may then be easily welded as at 23 to the adjacent end of an adjacent pair of rectangular rectilinear tubes 15. If any excess metal is provided it may be ground off or otherwise smoothed off to provide a flush surface such as is shown in Figure 4. Preferably the diameter of the connector 20 is the same as the diameter of the tubes 15, to provide a maximum contact with the inner faces of the walls 16 and 17.

In the particular plate shown in Figure 1, I illustrate a connector 24 having a nipple 25 to receive the end of the refrigerant inlet 9 or of any elbow or connector member applied thereto. One branch of the connector 24 extends to the coil C and the other to an intermediate passage or duct 26 which extends to the upper tube 15a of the coil D. A discharge fitting or connector 27 is employed, one arm of which receives the outlet duct 28 of the coil C. The nipple 30 is in communication with any suitable fitting and is adapted to connect it with the evaporant return duct 10. It will be understood that any suitable eutectic may be located within the space within the walls 16 and 17. Preferably I also subject the space within the plate to a vacuum. 31 indicates any suitable fitting or valve enclosure where the eutectic fluid may be admitted to the space between the walls 16 and 17 through

an inlet 32 controlled by a removable plug 33. After the eutectic fluid has been introduced I may employ the fitting 31 as a means for exhausting the air from the interior of the plate to provide a partial vacuum. The ball 34 serves as a check valve against the entry of atmospheric air. 35 is any suitable drainage fitting for draining the eutectic liquid from the interior of the plate.

In Fig. 2 I illustrate a form of plate the interior of which is largely filled by a eutectic fluid, the top level of the fluid being indicated at X. It will be understood that the volume of the fluid may be varied but that I prefer substantially to fill the interior of the plate, while leaving adequate space to take up the expansion of the fluid when it freezes. The fluid not merely serves as a hold-over, but provides the necessary moisture for maintaining a heat transmitting film between the opposed outer side faces of the coil lengths 15 and the inner faces of the side walls 16 and 17. If the fluid is admitted through the connector 31, it is free to fill the interior of the plate. In order to permit the liquid to flow to the entire space within the plate, I may slightly reduce the diameter of the curved bent portions 20, at least locally. Or it may be convenient to provide an additional inlet, not herein shown, to assist in the rapid filling of the plate.

In the form of Fig. 6, I use a much smaller volume of fluid, illustrated at Y. The hold-over factor, in the form of Fig. 6, is omitted, but enough liquid is delivered to the interior of the plate to provide the necessary moisture for maintaining the heat transmitting films between the opposed faces of the coil lengths 15 and the side walls 16 and 17.

It will be realized that, whereas, I have described and illustrated a practical and operative device, nevertheless many changes may be made in the size, shape, number and disposition of parts without departing from the spirit of my invention. I therefore wish my description and drawings to be taken as in a broad sense illustrative or diagrammatic, rather than as limiting me to my precise showing.

For example, I may employ a single coil within the cold plate instead of using the two coils which I show connected in parallel, as shown in Figure 1. I may also employ any suitable means for spacing or supporting the coils in a plate. I illustrate for example, the supports or spacers 40 in Figure 1 which may be employed in any suitable size, shape, number, and location.

A convenient and valuable embodiment of my invention is a coil having a plurality of rectilinear tubes of rectangular cross section, the tubes being connected to form a continuous coil, but pre-formed or separately formed connectors which may advantageously be non-rectangular, or circular in internal cross section.

It will be understood, for example, that I may, within the scope of my invention and within the terms of my claims, employ a unitary tube structure in which a rectangular tube is actually bent, and I do not wish to limit myself either to the employment of separate connecting portions or to the specific form or contouring or curvature of the connecting portions, since my invention includes any fluid conductive connection between adjacent rectilinear duct lengths.

The use and operation of the present invention are as follows:

The efficiency of the plate herein shown and claimed depends upon the adequacy of the heat

transfer between the coil, within which the refrigerant is evaporated, and the opposed side walls 16 and 17 of the plate. Sufficient fluid is admitted to the interior of the plate to permit the building up of films. The area occupied by the films is extended by the employment of square tubing, involving a substantial increase of direct heat transfer area, as contrasted to structures in which round or oval tubing is employed.

10 The liquid, such as a eutectic, provides the necessary material for the films, whether only a small volume is admitted, as in Fig. 6, or whether a large volume is admitted, as in Fig. 2. In the form of Fig. 6, it may be desirable to agitate the plate, to obtain an initial distribution of the liquid, before exhausting the interior of the plate. In both forms of plate the interior is sufficiently exhausted to maintain a substantial atmospheric pressure against the side walls of the plate. The 15 pressure differential may vary widely as desired, depending upon the size of the over-all area of the plate and on the gauge of sheet metal used for the plate side walls. It may, for example, vary within the range of 4 inches or less, of vacuum, to 20 25 20 inches or more, of vacuum. The effect of atmospheric pressure against the side walls is to maintain a very close contact between the inner faces of the walls and the opposed side faces of the tubing. This pressure differential results in 30 a heat transfer rate as good as those of the metal itself, and far better than the heat transfer condition existing where metals are welded, brazed, or soldered together. The procedure is simple, and easily and quickly carried out. The result is 35 a cold plate having very efficient heat transfer characteristics between the refrigerant in the interior of the coil, and the exterior of the plate.

An important function of the rectilinear tubes is to provide an internal reinforcement for the plates. The plates of the type herein shown are frequently in use in freezing presses and are subjected to heavy pressure in order to compact the substances undergoing freezing between adjacent plates. The provision of rectilinear tubes has the 40 double function, in a structural sense, of resisting inward pressure against the side of the plate, and of holding the outer surfaces of the opposite faces or sides of the plate to true and parallel planes. Thus when the coil structure is positioned within 45 50 the plate and the plate interior is partly exhausted, the outer pressure of the atmosphere against the walls of the plate maintains the plate as a strong structural element, having substantially true planes at each side, the planes of the 55 outer surfaces of the two sides of the plate being substantially parallel.

This application may be regarded as a continuation in part of co-pending application 571,863 filed January 8, 1945.

60 I claim:

1. In a vacuum plate adapted for use in refrigeration, and adapted to resist heavy pressures, a coil structure including a plurality of parallel rectilinear duct lengths and connecting bends, 65 said rectilinear lengths being generally rectangular in cross section and having outwardly plane top and bottom walls and connecting outwardly plane side walls perpendicular thereto, all of said top walls having outer faces lying in substantially the same plane and all of said bottom walls having outer faces lying substantially in a single plane parallel to said first plane, a housing including walls sealed together around their edges, each said wall abutting against the plane 70 surfaces of one side of said coil structure, and means 75

for maintaining a partial vacuum in the space within said walls and about said coil structure sufficient to maintain said walls firmly pressed against, and in intimate contact with, the opposed generally plane top and bottom surfaces of the coil, said parallel rectilinear duct lengths being sufficient in number and being sufficiently closely spaced to form a reinforcement for said housing walls, and to maintain the outer surfaces of said housing walls generally plane.

2. The structure of claim 1 characterized by and including a eutectic liquid positioned within said plate in the space within said housing and exterior to said coil structure.

3. The structure of claim 1 characterized by 15

and including a eutectic liquid positioned within said plate in the space within said housing and exterior to said coil structure in a volume approximating but somewhat smaller than the total volume of such space.
